[57] CLAIM

The ornamental design for a rotary high pressure water jet cleaning tool, as shown and described.

DESCRIPTION

FIG. 1 is a right side elevational view of a rotary high pressure water jet cleaning tool, showing my new design;

FIG. 2 is a bottom plan view thereof;

FIG. 3 is a left side elevational view thereof;

FIG. 4 is a top plan view thereof;

FIG. 5 is a rear elevational view thereof;

FIG. 6 is a front elevational view thereof; and

FIG. 7 is a front, bottom perspective view thereof. The broken-line showing of the connecting tubing elements is for illustrative purposes only and forms no part of the claimed design.

FIG. 1

FIG. 2

FIG. 3

FIG. 4

FIG.5

FIG.6

FIG. 7
